UNITED STATES PATENT OFFICE

CLARENCE C. WILSON, OF BRIDGEPORT, CONNECTICUT, ASSIGNOR TO THE COMPRESSED PAPER BOX CORPORATION, OF BRIDGEPORT, CONNECTICUT, A CORPORATION OF CONNECTICUT

DISPLAY BOX

Application filed June 13, 1929. Serial No. 370,546.

This invention relates to boxes adaptable for either shipping or displaying articles of merchandise.

It is an object of this invention to provide a box that is quickly and easily convertible from the closed shipping or storage formation to open or display formation without the necessity of removing or handling the merchandise therein.

10. It is a further object of this invention to provide a box having an insert adapted to be either nested therein or to cooperate with the cover to exhibit the merchandise at a display angle.

15. It is an additional object to provide a display box wherein the several elements are securely fastened or hinged together, wherein the hinging means shall be of maximum strength compatible with the materials used, 20 and yet may be manufactured and assembled very economically.

With the foregoing and other objects in view, the invention consists in certain novel features of construction, combinations and 25 arrangements of parts, as will be more fully described in connection with the accompanying drawings.

In the drawings

Fig. 1 is a front plan view of a box embodying this invention shown in display formation.

30. Fig. 2 is a sectional view on line 2—2 of Fig. 1.

Fig. 3 is a longitudinal section through the 35. box in closed shipping or storage formation.

Fig. 4 is a section through the hinge means between the cover and the base or bottom.

Fig. 5 is a section through the hinge means between the insert and the base.

40. The shipping and display box herein disclosed comprises a base or bottom portion 11 having a complementary cover 12 hinged thereto at one end and a nestable insert merchandise receptacle 13 hinged thereto at its other end. Fastened to the receptacle 13 is a decorative tassel 14 which serves to act as part of a background for the merchandise 15, herein shown as part of a salt and pepper set, but which obviously can 45. be any type of merchandise. In addition and

mainly, the tassel 14 serves as a handle or means to raise the receptacle 13 out of its nested shipping position, as in Fig. 3 to the display position after the cover 12 has been opened to the position, as in Figs. 1 and 2. 55

The nested receptacle or inner section 13 projects beyond the base or bottom 11 as at 16 so as to cooperate with the cover when in closed position, and is cut away as at 17 to the recessed portion 18 to better display the merchandise, that it may be visible even when looked at from the side of the box, as shown in Fig. 2. This insert or inner section takes the place of the usual neck provided in the tower section of boxes to telescope into and hold the cover section. 60

A foldable easel 19 serves to retain the insert 13 in display position in cooperation with the cover 12. The easel 19 may be omitted, however, and strip 20 pasted or secured with in cover 12 will cooperate with the free end of the insert 13 and likewise retain it in display position. 70

The means for hinging the cover 12 and the nested insert 13 to the bottom 11 are such as may be easily and economically manufactured, yet will provide the maximum holding strength. The hinge means between the cover 12 and the bottom 11 comprise a flexible strip 21 pasted or otherwise secured along the inner edge 22 of bottom 11 and along the outer edge 23 of cover 12. On the outer edge 24 of bottom 11 another strip 25 is secured and is pasted on the back of strip 21 along edge 23, but extends beyond the end of strip 21 and is also pasted directly to edge 23. These strips may be covered with or be of the same material as the covering material of the box so that the box has the same exterior finish throughout. It will be noted that a neat and strong hinging means between the cover and bottom is thus secured. 85

The other end of bottom 11 has the hinge means for the nested insert 13 secured along its outer edge 26. This hinge means comprises a strip 27 pasted on edge 26 of the bottom and pasted along the bottom edge 28 of the nested receptacle 13. Another strip 29 is pasted to edge 26 on and beyond strip 27, and is pasted to the upper or projecting edge 90

30 of the nested receptacle 13. It will be noted that the hinge means herein described will securely support the receptacle in display position, yet is very economical to manufacture. In operation, the merchandise 15 rests in a conventional decorative cloth or velvet filler 31 in the nested receptacle 13 which is supported by a suitable frame 32 of cardboard or other suitable material mounted in 10 back of said cloth, and is closed and packed as shown in Fig. 3. When the merchant receives the box, he raises the cover 12 and then lifts up the tassel 14, thereby withdrawing the receptacle 13 from its nested position and 15 rests it in display position in cooperation with the cover in a general triangular form either by extending the easel 19 or resting the edge of the receptacle on strip 20, depending on which form has been provided.

20 Having thus set forth and described the invention, what is claimed is:

1. A container adapted for shipping or displaying its contents comprising a base receptacle, a complementary cover hinged at one 25 end thereto, an insert receptacle hinged at one end to the other end of said base receptacle and nesting therein when in shipping formation, the hinged end of the insert being higher than the other walls of the insert and 30 the base and adapted to cooperate with said cover when in closed position, and said insert adapted to cooperate with the cover to exhibit its contents when in display formation.

35 2. A container comprising a base receptacle, a complementary cover hinged at one end thereto, an insert receptacle hinged at the upper edge of the other end of and nestable in 40 said base, said insert hinged to the base intermediate its upper and lower edges and projecting beyond said base when nested therein, whereby to cooperate with said cover when in closed position, said insert and cover cooperating to exhibit the merchandise in display position by holding the free end of the 45 insert raised from the base.

3. A display and shipping box comprising a base receptacle, a cover complementary thereto, means for hinging said cover to one 50 end of said base, an insert receptacle nestable in and projecting above said base receptacle, means for hinging said insert to the other end of said base, said last means comprising a strip secured outside said base and 55 outside said insert on said nesting portion, and a second strip secured outside said base on and beyond said other strip and secured outside said insert on said projecting portion.

60 4. A display and shipping box comprising a base receptacle, a cover complementary thereto, means for hinging said cover to one end of said base, and insert receptacle nestable in and projecting above said base receptacle, means for hinging said insert to the 65 other end of said base, said last means com-

prising a strip secured outside said base and outside said insert on said nesting portion, a second strip secured outside said base on and beyond said other strip and secured outside said insert on said projecting portion, and 70 means for supporting said insert at an angle to said base and cover for displaying its contained merchandise.

5. A display and shipping box comprising 75 a base receptacle, a cover complementary thereto, means for hinging said cover to one end of said base, an insert receptacle nestable in and projecting above said base receptacle, means for hinging said insert to the other end of said base, said last means 80 comprising a strip secured outside said base and outside said insert on said nesting portion, and a second strip secured outside said base on and beyond said other strip and secured outside said insert on said projecting portion, and means comprising a supporting strip secured inside said cover near its free end.

6. A shipping box adapted to display its 90 contents, said box comprising a base including side and end walls, a cover including side and end walls, said cover being hinged at the lower edge of one of its walls to the upper edge of one of the walls of the base, a nested receptacle portion, said nested portion including side and end walls, and one of the walls of said nested portion hinged intermediate its upper and lower edges to the upper edge of the wall of the base opposite the wall to which the cover is hinged.

In testimony whereof I affix my signature.
CLARENCE C. WILSON.
